**SPRAY NOZZLE FOR CLEANING THE INTERIOR
OF TANKS OR THE LIKE**

Victor P. Boka, Jr., 9771 Allen Road, Allen Park, Mich.,
and John A. Herman, 461 Kings Highway, Wyandotte,
Mich.

Filed Apr. 6, 1959, Ser. No. 55,367

Term of patent 14 years

(Cl. D91—1)

Fig. 1 is a front perspective view of a spray nozzle for cleaning the interior of tanks or the like, showing our new design;

Fig. 2 is a rear elevational view thereof on a reduced scale; and

Fig. 3 is a bottom plan view thereof.

The dominant features of our design reside in the portions shown in full lines.

We claim:

The ornamental design for a spray nozzle for cleaning the interior of tanks or the like, as shown and described.
